UNITED STATES PATENT OFFICE.

ADOLPH L. BERGER AND DAVID GREGG, OF DAYTON, OHIO.

AUTOMATIC REGULATOR FOR TURBO SUPERCHARGERS.

Application filed September 12, 1923. Serial No. 662,361.

To all whom it may concern:

Be it known that we, ADOLPH L. BERGER and DAVID GREGG, citizens of the United States, residing at Dayton, in the county of 5 Montgomery and State of Ohio, have invented certain new and useful Improvements in Automatic Regulators for Turbo Superchargers, of which the following is a specification.

10 This invention relates to a regulating device for a turbo supercharger of the kind used in aircraft for the regulation of the air pressure supply to the carburetor of an internal combustion engine for high altitude 15 use.

The object of this invention is to provide an automatic regulation of the turbo supercharger so as to maintain the air supply to the carburetor or carburetors at any desired 20 pressure; and one in which the fluctuations in the air pressure are minimized as far as possible.

A second object is to provide a reversible electric motor for slowly opening and closing the waste gate to provide an automatic regulator for the exhaust gases leading to the turbine driven supercharger.

Further objects will be more fully set forth in the attached specification and 30 claim.

In the drawings:

Fig. 1 is a diagrammatic view of the entire apparatus showing the electrical connections between the reversible electric motor and the contact controlling device and also showing schematically the fluid passages 35 of the supercharger.

Fig. 2 is a diagram of the electrical connections and

40 Fig. 3 is a vertical section through the center of the contact controlling box.

Referring to the drawings by reference numerals, 1 indicates the cylinder of an internal combustion engine having an inlet 45 valve 2 and an exhaust valve 3. The exhaust valve conducts the gases from the cylinder to an exhaust pipe 4 which leads to a chamber or nozzle box 5 having nozzles or outlets 6 through which the exhaust gases 50 issue and drive the turbine blades of the turbine 7. The gases expand as they pass through the nozzles and acquire a high velocity before they enter the blades or buckets of the turbine wheel which is thereby driven 55 at high speed. An impeller 8 which is directly connected to the turbine wheel 7

and rotated thereby in a casing 9 supplies air under pressure to an air intake pipe 10, taking this air from suitable openings in the casing 9 which lead to the external atmosphere. 60

The air under pressure in the pipe 10 is supplied to a carburetor 11 which is connected in the customary manner so as to supply a gas mixture to the cylinder of the engine. The air entering the carburetor is maintained at any desired pressure within the capacity of the supercharger by the operation of a waste gate 12 which is automatically governed in a manner as will be more 65 fully described so as to permit, at times, part of the exhaust gases to be released or wasted through this gate, and cut down the supply leading to the nozzle box. 70

The waste gate 12 which is shown as a 75 flapper valve, is connected by a suitable link arrangement 13 to a reciprocating rod 14 having threads 15. A reversible electric motor 16 drives a worm 17 which operates a worm wheel 18 rotatably mounted upon the 80 rod 14 and held against axial displacement by an abutment 19 and a projection or flange 20 formed as parts of the housing of the rod and worm adjusting mechanism. The worm gear 18 is rigidly connected by means of 85 bolts 21 to a sleeve 22 interiorly threaded so as to engage the threads 15 of the rod 14. It will therefore be understood that a rotation of the motor in one direction rotates the sleeve 22 so as to move the rod 14 in one direction, and an opposite rotation of the motor will operate in a similar manner to move the rod 14 in a reverse direction, so as to control the opening of the exhaust gate 12. In

Fig. 1 the gate 12 is shown in its closed position, the rod 14 being at its extreme position to the right as shown in this figure. 90 In normal operation, the gate 12 is maintained slightly open so as to permit the electric motor to control this gate in either direction. That is, to either open or close it. The movements of the gate due to the electric motor, are comparatively slow because of the slow movements of the rod 14 so as to permit the control of the motor to function 95

before the gate is fully moved in either direction. The pressure of the air supplied by the supercharger is therefore maintained exceedingly steady.. 100

In order to control direction of rotation 110 of the motor, a contact-making device is provided in a housing 23, this housing be-

ing closed with the exception of an opening provided so as to connect the housing with a pipe 24 leading to the air intake pipe 10. Within this housing is a closed bellows 25 attached at 26 to the side wall 27 of the housing. This closed bellows provides a flexible sealed chamber which expands when the surrounding air pressure decreases, or contracts when the surrounding air increases, the surrounding air pressure, of course, being the same as that supplied to the carburetor. The bellows 25 is connected by means of a pivot 28 on an integral projection 29 of the bellows to a lever 30 pivoted at the point 31 upon a suitable support within the housing for this lever. This lever 30 carries four contact points 32, 33, 34 and 35, contacts 32 and 34 being at all times electrically connected to a stationary terminal 36 connected to the field winding of the motor and contacts 33 and 35 being connected in a similar manner by means of a flexible conductor 37 to the terminal 38 which is connected to a source of power which in this case is shown as a battery 39. The contacts 32 and 33 are adapted to make contact with terminals 40, 41 when the lever is moved toward the left (see Fig. 3). Terminals 40 and 41 are both connected to the armature of the motor. Other terminals 42 and 43 are likewise connected to the armature of the motor and are adapted to coat with the contacts 34 and 35 when the lever 30 is moved to the right from the neutral position shown in Fig. 3. When the lever 30 is moved in one direction the electric motor is connected to the source of power and rotated so as to close the gate 12, and opening movements of the gate 12 are caused by a reverse movement of the lever 30 and the contacts carried thereby.

Since the air within the closed chamber 25 is permanently sealed therein, any change in pressure of the air within the pipe 10 causes a corresponding change in pressure in the housing of the contact closing mechanism and induces a movement either expansion or contraction of the closed chamber or bellows 25. As the contact-making mechanism is rather sensitive and is governed entirely by changes in pressure of the air within the pipe 10 and as the translational movements of the rod 14 are small for the corresponding rotational movements of the motor, it will be seen that the gate 12 is moved through a very small distance toward or away from its neutral position in order to maintain a constant air pressure supply to the engine.

We claim:

An automatic control for a turbine driven supercharger for internal combustion engines in which the engine exhaust is used for driving the supercharger fan, comprising in combination, a waste gate in the exhaust manifold of the engine, an electric motor having reversible connections to reverse the direction of rotation thereof, speed reducing means connecting said motor to said waste gate to cause the waste gate to be slowly moved by said motor, and an automatic switch controlling the reversible connections of said motor, said switch having a movable element actuated by difference in pressure between the outlet of said supercharger fan and normal atmospheric pressure.

In testimony whereof we affix our signatures.

ADOLPH L. BERGER.
DAVID GREGG.
